DISPLAY DEVICE

Filed June 19, 1929

UNITED STATES PATENT OFFICE

WILHELM SWENSON AND GORDON C. SWENSON, OF ERIE, PENNSYLVANIA
DISPLAY DEVICE

Application filed June 19, 1929. Serial No. 371,996.

It is very desirable in carrying different kinds of display matter, such as advertising, to provide a carrying strip for the display which will advance intermittently and have sufficient interval between each advance to permit the ready observation and reading of any display matter that there may be exposed. In order that the strip may have considerable length it is preferable to mount it upon rolls at the ends and that the strip after it has completed its length be reversed so that the operation of the strip back and forth may continue as long as desired.

The control of such devices is important both as to the making and breaking of the driving mechanism so as to make the advance intermittent. The matter of giving a sufficient interval between each advance, and the matter of reversal, is also of importance. The present invention accomplishes these different functions in a simple and economical manner.

It is also desirable to compel the final stoppage of the strip at one of the points of advance so that the display which is left in view may be complete. The present invention also provides for this. Features and details of the invention will appear from the specification and claims.

A preferred embodiment of the invention is illustrated in the accompanying drawings as follows:—

Fig. 1 shows a diagrammatical view of the apparatus.

Fig. 2 a perspective view of the apparatus as it appears in use.

Fig. 3 a detail of the contact mechanism for the strip control.

Fig. 4 a yielding retarding device for retarding the snap shift of the reversing mechanism.

Fig. 5 an alternative construction of control of the electric circuit.

Fig. 6 a second alternative means of effecting the electric control through the action of the strip.

Fig. 7 a section on the lines 7—7 in Figs. 1 and 8.

Fig. 8 a section on the line 8—8 in Fig. 7.

Fig. 9 is a perspective view of the trip device of the timing mechanism.

1 marks the display strip. This is preferably of some non-conducting material, ordinarily oil-cloth being one form of possible material. This strip passes over a lower guide roll 2 and an upper guide roll 3, these rolls being carried by shafts 4 suitably mounted in bearings (not shown). The lower end of the strip is mounted on a roll 5 and the upper end of the strip on a roll 6. A gear 7 is fixed with the roll 5 and a pinion 8 is adapted to mesh with this gear. The pinion is fixed on a shaft 9. A gear 10 is fixed with the roll 6 and a pinion 11 fixed on the shaft 9 is adapted to be thrown into mesh with the gear 10. The shaft 9 is slidably and rotatively mounted in bearings (not shown).

The strip is provided with reversing bars 12 and 13. These bars are secured to the strip near the ends of the strip and project beyond the edges of the strip. The bar 12 is adapted to engage a shift lever 14. This lever is U-shaped engaging the bar 12 at both edges of the strip and is pivoted on pins 15. A spring 16 extends from the lever 14 to a lever 17. The lever 17 is pivoted on a pin 18. A link 20 is connected by a pin 19 to the lever 17. A lever 21, similar to the lever 14, is pivoted at 22 and is in the path of the bar 13. It is connected by a spring 23 with a lever 24. The lever 24 is pivoted on a pin 25. The link 20 is secured to the lever 24 by a pin 26. The link 20 is connected to the lever 27 by a pin 28. The lever 27 is pivotally mounted at 27a. The lever is provided with a forked end and connected by pins 29 with a sleeve 30. The sleeve 30 is rotatively mounted on the shaft 9 but locked against endwise movement relatively thereto. A yielding detent 31 is mounted on the lever 27 and is adapted to be yieldingly forced forward by a spring 32 (See Fig. 4). It is adapted to traverse a segment 33 and to be engaged by notches 34.

In the operation of the reversing device, when the lever 14, or 21, is engaged by the bar 12, or 13 respectively the spring 16, or 23, as the case may be is loaded and extended

until the yielding detent 31 is overcome, when there is a snap shifting of the shaft 9 throwing the gear 8, or the gear 11, into mesh with the gear 7, or the gear 8, depending on the direction of the shaft. Thus the direction of movement of the strip is reversed.

A gear 35 is connected with the shaft 9 by a spline 36. It meshes with a pinion 37. The pinion 37 is fixed on a shaft 38. A clutch cone 39 is splined on the shaft 38 by a spline 40 and is adapted to slide forward, or back, on said shaft. A spring 40a tends to set the clutch. A clutch disc 41 is adapted to receive the cone 39. It is fixed on a shaft 42. A gear 43 is fixed on the shaft 42 and is driven from a gear 44. The gear 44 is fixed on a shaft 45 which is connected with the driven shaft of an electric motor 46.

The strip is provided at intervals with perforations 47 and the controlling contact for the motor is made by brushes which make contact through these perforations, or are insulated by the strip itself. Thus a very convenient control is provided by means of which the intervals, or length of travel of the strip may be easily controlled, as desired. The guide roll 2 is provided with a conducting band 48 at its outer end. A brush 49 operates on this band. The brush is pivoted at 50 and is held in contact by a spring 51. Line wires 52 and 53 supply the motor. A branch 54 extends from the wire 52 to the brush 49. A similar brush 55 is arranged to operate on the strip and in the path of the perforations 47 so that when the perforations register with the brush contact is made by the brush with the conducting ring 48 and thus with the brush 49. The brush 55 is pivotally mounted at 56 and held in contact by a spring 57. A wire 58 extends from the brush 55 to a switch 59 and thence by a wire 60 to a solenoid 61 and from the solenoid to the wire 53 by a wire 62.

A lever 63 is pivotally mounted on a pin 64 and a link 65 is connected with the lever by a pin 66. The link 65 extends to a lever 67. The lever 67 is pivoted on a pin 68 and is provided with a fork at its end which is connected by pins 69 with a sleeve 69a extending from the cone 39. It will readily be seen that as the lever 63 is moved toward the left the clutch will be drawn out to the position shown in Fig. 1. A shoulder 70 is arranged on the lever 67 and this is caught by a latch 71 when the clutch is released. The latch 71 is moved to engaging position by a spring 73 so that when the clutch is opened through the action of the lever 63 it is locked in open position by this latch.

The active element of the solenoid is connected with the lever 63 by a pin 61a. It will readily be seen that as the circuit is closed by the brush 55 that the solenoid becomes active and moves the lever and releases the clutch. A pulley 74 is fixed on the

shaft 45 and drives a pulley 76 by means of a belt 75. The pulley 76 is fixed on a shaft 77 and this shaft has a screw thread 78. The shaft is journaled in posts 79. A sleeve 80 extends between the post 79 and around the screw 78. This sleeve has a longitudinal slot

81 and a segmental nut 82 formed in two branches connected by a cross bar 83 is adapted to extend through the slot 81 into engagement with the threads of the screw 78. The two parts of the segmental nut straddle cams 84 arranged in a slot 85 in a timing frame 86. The timing frame is slidely mounted on the tube 80. A guiding arm 87 extends from the frame 86 and engages

a guide rod 88 which locks the frame from turning on the tube 80. A pin 89 extends from the segmental nut and is pressed forward by a spring 90, thus yieldingly pressing the nut into engagement when the nut is released from the control of the cam 84.

A controlling arm 91 extends from the cam and this is adapted to be engaged by a cam 92 on the end of a lever 93. The lever 93 is pivoted on a pin 94 and is connected by a link 95

with the lever 63. So that when the lever 63 is operated in response to the activity of the solenoid the cam 92, acting on the arm 91 rotates the cam 84 and releases the segmental nut which, under the influence of the

spring, engages the thread. The frame 86 then begins the traverse of the tube through the action of the screw 78. As it advances, the arm 96 passes over and rests on the platform 96 and on further advance engages a

lever 97. This lever 97 is forced downwardly by a spring 100 so that as the arm passes off the platform 96 it is immediately tripped by the lever 97 which has loaded the spring 93 as it is forced upwardly by the arm as it

moves forward over the platform 96. The arm snaps down as it moves off the platform, as indicated in Fig. 9, throwing the cam 84 into position to release the nut and the frame is then automatically retracted, the arm passing under the platform 96 in the return movement.

A cord 101 extends from the frame 86 to a spring 102, the cord being carried around a pulley 103. This spring retracts the frame 86 when the nut is released and re-sets it at the new position.

A switch 104 in the line of the wire 58 leading to the solenoid is closed with the frame 86 in its initial position but as soon as the frame 86 has started to travel the switch 104 is opened so that current is cut off of the solenoid and thus the consumption of current is reduced.

As the frame advances through the action of the screw, which we term the timing device, the frame has a post 105 which contacts a finger 106 carried by the latch 71. When, therefore, the frame has practically completed the traverse of its movement it contacts this finger 106, trips the latch 71 and

110

permits the re-setting of the clutch and thus another advance of the display strip.

It is desirable to compel the final stoppage of the strip at a point which will leave one of the display features of the strip in its proper location at the point of advance. This is accomplished by a switch mechanism 107. A line wire 108, companion to the line wire 52 extends to a three-way switch 109. This three-way switch has posts 110, 111, 112, and 113 and a switch blade 114 adapted to connect the posts 110 and 113, or the posts 112 and 111. The wire 108 is connected with the post 110 and through a wire 115 with the post 111. The post 113 is connected by a wire 116 with a switch blade 117. A switch blade 118 has a contact finger 119 engaging the blade 117. A wire 120 extends from the blade 118 to the wire 53. The lever 97 has an extension 121 which is adapted to engage the end of the blade 118 and open the contact between the finger 119 and the blade 117. In operation, with the switch set between 111 and 112 there is a direct connection between the wire 108 and the wire 53 and thus the apparatus may be started and continue to run. When it is desired to stop the apparatus the blade 114 is thrown between the posts 110 and 113. Current will then pass, by way of the wires 116, blade 117, contact fingers 119, blade 118, and wire 120 to the wire 53 and this will continue until the frame 86 contacts the lever 97 at one of the points of stoppage in the advance of the strip and this lifting of the lever 97 depresses the extension 121 and opens the circuit and finally stops the machine. The parts remain in this position until the switch 109 is thrown connecting the posts 111 and 112.

It will be noted, therefore, that with this apparatus there is a strip which may be of very considerable length and that it is in a simple manner intermittently advanced and stopped making the proper display at intervals and that it is provided with a reversing mechanism which will reverse the strip automatically at the ends of the travel of the strip; that it is provided with a timing device by which the interval between each advance may be controlled as desired; and that it is driven by a constantly operating motor and that the intermittent advance is controlled by the setting and release of a driving clutch. It will also be noted that the current control is directly responsive to conductivity conditions in different parts of the strip itself.

In Fig. 5 we have shown an alternative construction in which the strip is provided with contact plates 122 which are adapted to engage brushes 123 and 124 corresponding to the brushes 49 and 55.

In Fig. 6 we have shown an alternative construction in which a contact bar 125 extends across the strip and is adapted to be

engaged by brushes 126 and 127 corresponding to the brushes 49 and 55 and controlling the circuits in the same manner.

What we claim as new is:—

1. In a display device, the combination of 70 a display strip; mountings for the strip; automatic means for advancing the strip intermittently comprising a clutch; a spring setting the clutch, an electric device moving the clutch to release it, and a latch holding the clutch in release position; and a timing device controlling the interval between the advances, said timing device controlling the release of the clutch.

2. In a display device, the combination of 80 a display strip; mountings for the strip; automatic means advancing the strip intermittently; an electric motor drive for the means; a timing device controlling the interval between advances; and a switch for the motor operative to cut off the current from the motor only during an interval between advances.

3. In a display device, the combination of 90 a display strip; mountings for the strip; automatic means advancing the strip intermittently comprising a timing device controlling the interval between the advances; and a control device actuated by the timing device for effecting the stoppage of the means only during an interval between advances.

4. In a display device, the combination of 100 a display strip; mountings for the strip; automatic means advancing the strip intermittently; a continuously actuated electric motor driving the means; a clutch in the drive; a spring setting the clutch; electric devices moving the clutch to release position; a control for the electric device responsive to differences in conductivity of the strip; a latch holding the clutch in release position; a timing device controlling the interval between advances, said timing device controlling the release of the clutch; and an electric control for the means effecting a final stoppage of the means only at one of the points of advance, said control device being actuated by the timing device.

In testimony whereof we have hereunto set 115 our hands.

WILHELM SWENSON.
GORDON C. SWENSON.
